AUTOMATIC FOUR DOOR LOCK FOR
AUTOMOBILES

Solomon Lesser, New York, N. Y.

Application February 25, 1939, Serial No. 258,370

4 Claims. (Cl. 70—264)

This invention relates to new and useful improvements in an automatic four door lock for automobiles.

The invention has for an object the association of mechanism with the four locks of the four doors of an automobile arranged in a manner so that the four locks may be locked simultaneously. The advantage of this arrangement resides in the convenience with which the doors may be locked merely by operating one lock.

Still further the invention contemplates a construction characterized by the use of flexible cables for transmitting the locking motion between the locks so that they may work in unison.

Another object of this invention resides in providing a toggle construction disposed between the front and rear doors at each of the sides of the automobile and arranged and connected with mechanism in a manner for controlling the bolts of the locks.

Another object of this invention resides in the provision of a manual means independent of the key controlled means for locking the locks and operative from within the vehicle body for moving one of the toggles previously mentioned for opening its associated lock in case of emergency.

Another object of the invention resides in providing locking mechanism for the windows of the vehicle also controlled by the door locking mechanism.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a side elevational view of an automobile with an automatic four door lock constructed according to this invention.

Fig. 2 is a perspective schematic view of the doors of the automobile and the associated locking mechanism.

Fig. 3 is a fragmentary vertical sectional view of a portion of the front and rear doors and the door jambs of these doors at the near side of Fig. 1.

Fig. 4 is a view similar to Fig. 3 of the doors at the far side of Fig. 1.

Fig. 5 is a fragmentary enlarged sectional view taken on the line 5—5 of Fig. 3.

Fig. 6 is a fragmentary enlarged sectional view taken on the line 6—6 of Fig. 3.

55 The automatic four door lock for automobiles,

according to this invention, is used in combination with an automobile body 10 having right side front and rear doors 11 and 12 respectively, and left side front and rear doors 13 and 14 respectively. These doors are provided with locking bolts 15, 16, 17 and 18, respectively. Each of these doors is of the hinge type and at their remote edges are provided with hinges 20 by which the doors are hingedly supported to swing open and close. Each of these doors work in a door jamb of the automobile. The doors at the right side of the automobile body are separated by a jamb partition 21 and the doors at the left side are separated by a jamb partition 22.

A key operated cylinder lock 23 is mounted upon the jamb partition 21. This lock is of the type having a rearward extending rod 23^a for working the bolt mechanism of the door locks. The rod 23^a is of elongated shape in cross section and is adapted to engage in the elongated opening 23^b of a rotatively supported gear 24. This gear is in mesh with a gear 25 rotatively supported and meshing with a rack 26. The rack 26 is connected with a vertically slidably mounted bar 27. This bar is supported by several bolts 28 mounted upon the material of the jamb partition 21 and working in vertical slots 29 formed in the bar. A toggle mechanism is disposed within the jamb partition 21 for locking and opening the bolts 15 and 16 respectively. This toggle mechanism includes arms 30 and 31. These arms at their inner ends are pivotally mounted on a spindle 32 which extends through the bar 27. At this point the bar is formed with a slot 33 the base portion of which is formed with an enlarged recessed opening 34.

A collar 35 is mounted on the spindle 32 and normally is disposed within the recess 34. An expansion spring 36 is arranged axially on the spindle 32 and acts between a head 37 formed on the inner end of the spindle and one side of the bar 27 for normally urging the collar 34 into engagement within the enlarged recess 34. The inner end of the spindle 32 is provided with a head 38 by which it may be manually moved. The arrangement is such that the head 38 may be pulled to compress the spring 36 and to move the collar 35 out from the recess 34. Then the toggle arms 30 and 31 are relatively free from the bar 27 and the spindle 32 may move along the slot 33.

Levers 39 and 40 are pivotally supported at their upper ends by pintles 41. Intermediate of their ends these levers are pivotally connected by pintles 42 with the toggle arms 30 and 31. The

55

lower ends of the levers 39 and 40 are formed with forked portions 39^a and 40^a respectively, engaging pins 43 mounted on brackets 44 which in turn are respectively mounted on the bolts 15 and 16. Each of these bolts has a slot 45 through which a supporting fastening element 46 passes to assist in horizontally slidably supporting the bolts. A cable 47 is connected with the upper end of the bar 27 and extends through a stationary casing 48 which is guided within the roof of the vehicle body 10.

When the gear 24 is turned by the cylinder lock the motion will be transmitted to move the rack 26 downwards. This indirectly moves the toggle arms 30 and 31 downwards at their inner ends so that their outer ends spread the levers 39 and 40. This motion extends the bolts 15 and 16 into the keepers for the bolts arranged upon the doors 11 and 12. The bolts 15 and 16 may be opened by operating the cylinder lock in the opposite direction to rotate the gear 24 back to its original position. It is pointed out that when the bar 27 is in its lowered position in which the bolts 15 and 16 are in their locked positions, it is possible to operate the emergency handle 38 to relatively disconnect the upper ends of the toggle arms 30 and 31 from the bar 27 and then the spindle 32 may be moved upwards to manually move the toggle arms 30 and 31 and so indirectly retract the bolts 15 and 16.

The bolts 17 and 18 are operated in a manner very similar to the bolts 15 and 16. Within the jamb partition 22 there is a vertically slidably mounted bar 27' which is supported by several bolts 28' working in slots 29' formed in the bar 27'. The top end of the bar 27' is connected with the flexible cable 47 so that when the bar 27 moves downwards the bar 27' will be moved upwards. Toggle arms 30' and 31' are pivotally connected at their inner ends by a pin 32' mounted on the bar 27'. The outer ends of the toggle arms are connected by pintles 42' with intermediate portions of levers 39' and 40'. These levers are pivotally supported at their lower ends by pintles 41. The upper ends of these levers have forked portions 39^{aa} and 30^{aa}, respectively. These forked portions engage pintles 43' mounted on brackets 44' which are directly supported on the bolts 17 and 18 respectively. Each of these bolts operate horizontally. Fastening elements 46' working in slots 45' formed in the bolts assist in supporting the bolts horizontally. When the cable 47 moves the bar 27' upwards the bolts 17 and 18 will be extended to their locking position and when the bar 27' is moved downwards the bolts will be moved back to their open positions.

Each of the doors is provided with a window 50 associated with mechanism for moving the window upwards and downwards controlled by the conventional turnable handle 51. The details of this mechanism will not be given in this specification since such mechanism is generally known in the art and is of the type shown in the patent issued to Jesse G. Vincent, No. 2,053,854, on September 8, 1936. However, a locking means is associated with each of the doors operated by the bolt of the door for locking the window 50 from being opened. This means includes a ratchet wheel 52 mounted on each handle 51. An arcuate pawl 53 is adjacent each ratchet wheel 52 and is slidably supported by fastening elements 54 working in horizontal slots 55 formed in a tail portion 53 of the arcuate pawl.

75 A spring 56 acts to normally hold the arcuate

pawl 53 from the ratchet wheel 52. Each tail portion 53^a is provided with a rod 56 which slidably extends into a bracket 57. A spring 58 is mounted upon the rod 56 and normally tends to separate the bracket 57 from the tail portion 53^a. The bracket 57 is disposed immediately adjacent the bolt of the particular door. The rod 56 has a cross head 56^a working in a slot 59 formed in the bracket 57 for slidably supporting the bracket. When the lock is opened the parts are as shown upon the drawing. However, when the bolt of any particular door is closed it will move the bracket 57 of the window locking mechanism inwards. This motion is transmitted by the spring 58 which is a relatively stiff spring as compared with the spring 56. The motion will therefore be transmitted to the arcuate pawl 53 which then acts against the ratchet wheel 52. The arrangement is such that the handle 51 may still be turned to close the window since the ratchet teeth will then slide past each other. But the window cannot be opened because the teeth engage each other. It is necessary that the bolt be first moved to an unlocked position before the window may be opened. The particular window locking mechanism is identical for each of the four doors.

The operation of the device is as follows:

When the doors of the automobile body are closed they may be simultaneously locked by operating the cylinder lock 23. This lock, when moved to the closed position, moves the bar 27 downwards. This motion is transmitted by the cable 47 to move the bar 27' upwards. The motion of these bars operates the toggle levers 39 and 31 and 30' and 31', respectively, which simultaneously extend the bolts 15, 16, 17 and 18. The four doors are now locked.

In the locked position of the doors the bolts engage the brackets 57 of the window locking means. These brackets are moved into positions in which the arcuate pawls 53 of the window locking means engage the ratchet wheel's 52. Then the windows may be closed but cannot be opened.

From the interior of the vehicle it is possible to open certain of the doors. This is accomplished by pulling the head 38 and then moving the spindle 32 upwards relative to the bar 27. This retracts the bolts 15 and 16. When the lock mechanism is thereafter operated to open the other two doors the bar 27 will move upwards and the collar 35 will snap into the recess 34 and now the parts are again in position in which the doors may be locked.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In an automobile body having a front and a rear hingedly mounted door on each of the sides thereof, a bolt for each door for locking said doors, a toggle between each front and rear door for locking and opening the bolts thereof, a movably mounted bar connected with each toggle for operating same, a transmission means between said bars to move them in unison, and manual means operative from within said automobile body for moving one of said toggles for opening its associated bolts, comprising a spindle 75

supporting the arms of said toggle, said spindle being provided with a collar engaging a recess in one of said bars, a spring urging said collar into said recess, and said spindle being movable to free the collar from the recess and so free the toggle arms from the bar.

5 2. In an automobile body having a front and a rear hingedly mounted door on each of the sides thereof, each of said doors having a window operating element adapted to move a window to an open or closed position; and controlled with a turnable handle, a bolt for each door for locking said doors, a toggle between each front and rear door for locking and opening the bolts thereof, a movably mounted bar connected with each toggle for operating same, a transmission means between said bars to move them in unison, and key controlled means for moving one of said bars, a ratchet wheel for each of said elements, 10 a pawl for each ratchet wheel engageable therewith for locking the ratchet wheel from turning in one direction, and means operative by said bolts for moving said pawls into operative or inoperative positions.

15 3. In an automobile body having a front and a rear hingedly mounted door on each of the sides thereof, each of said doors having a window operating element adapted to move a window to an open or closed position; and controlled with a turnable handle, a bolt for each door for locking said doors, a toggle between each front and rear door for locking and opening the bolts thereof, a movably mounted bar connected with each toggle for operating same, a transmission means 20 between said bars to move them in unison, and key controlled means for moving one of said bars, a ratchet wheel for each of said elements, a pawl for each ratchet wheel engageable therewith for locking the ratchet wheel from turning in one 25 direction, and means operative by said bolts for moving said pawls into operative or inoperative positions, comprising a bracket slidably supported, a spring interposed between said bracket and pawl, and a weak spring urging the pawl into an open position.

30 35 means between said bars to move them in unison,

and key controlled means for moving one of said bars, a ratchet wheel for each of said elements, a pawl for each ratchet wheel engageable therewith for locking the ratchet wheel from turning in one direction, and means operative by said bolts for moving said pawls into operative or inoperative positions, comprising a bracket slidably supported, a spring interposed between said bracket and pawl, and a weak spring urging the 5 pawl into an open position.

10 4. In an automobile body having a front and a rear hingedly mounted door on each of the sides thereof, each of said doors having a window operating element adapted to move a window to an open or closed position; and controlled with a turnable handle, a bolt for each door for locking said doors, a toggle between each front and rear door for locking and opening the bolts thereof, a movably mounted bar connected with each toggle for operating same, a transmission means 15 between said bars to move them in unison, and key controlled means for moving one of said bars, a ratchet wheel for each of said elements, a pawl for each ratchet wheel engageable therewith for locking the ratchet wheel from turning in one 20 direction, and means operative by said bolts for moving said pawls into operative or inoperative positions, comprising a bracket slidably supported, a spring interposed between said bracket and pawl, and a weak spring urging the pawl into 25 an open position, said pawl being slidably supported, and when said bracket is moved the stiff spring serving to move the pawl into operative position.
